UNITED STATES PATENT OFFICE

153,268

DESIGN FOR A BOXLIKE CONTAINER

Wilfred A. Eaton, Woodbury, Conn., assignor, by
mesne assignments, to Sanford Products, Inc.,
Woodbury, Conn., a corporation of Delaware

Application December 29, 1945, Serial No. 125,182

Term of patent 14 years

(Cl. D58—12)

To all whom it may concern:

Be it known that I, Wilfred A. Eaton, a citizen of the United States, residing at Woodbury, in the county of Litchfield and State of Connecticut, have invented a new, original, and ornamental Design for Box-Like Containers, of which the following is a specification, reference being had to the accompanying drawing, forming part thereof.

Fig. 1 is a perspective view of the box-like container, showing my new design;

Fig. 2 is a front elevational view of the design shown in Fig. 1; and

Fig. 3 is a side elevational view of the design shown in Fig. 1; and

Fig. 4 is a rear elevational view of the design shown in Fig. 1.

The dominant features of my design reside in the portions shown in full lines.

I claim:

The ornamental design for a box-like container, substantially as shown and described.

WILFRED A. EATON.
